ROBERT KERR AND JOHN PINKERTON KERR, OF PAISLEY, SCOTLAND.

Design No. 3,819, dated January 18, 1870.

DESIGN FOR A TRADE-MARK.

The Schedule referred to in these Letters Patent and making part of the same.

To all whom it may concern:

Be it known that we, ROBERT KERR and JOHN PINKERTON KERR, of the town of Paisley, in the county of Renfrew, Scotland, have invented and produced a new and original Design for a Trade-Mark, of which the following is the specification.

Our design is composed of the symbolical character or mark, usually employed, in the United States, to represent or designate the American dollar, when written in figures, by being placed before the figures specifying the number of dollars, this character forming the central figure of our design.

This central figure is encircled by three concentric rings, the two inner ones being near each other, while the distance between the second and the outer rings is greater, so as to form an annular space, within which space are the words "The Standard Thread," in capital letters, occupying about three-fourths thereof.

On the remaining portion of this space is a shield, on which are figures or numerals, representing the size of the thread.

The object and effect of the whole of this design are to produce a systematic, neat, and, at the same time, distinctive and novel mark, by which we intend that a specific kind of thread shall be known and recognized by the trade and the public.

We intend, by this mark, to distinguish it, without mistake, from all other kinds of thread, whether manufactured by us, or by any other person or persons.

Having thus described our design,

What we claim, and desire to secure by Letters Patent of the United States, is—

The design for a trade-mark for thread, as herein shown and described.

ROBERT KERR.
